US0D1113019S

(12) **United States Design Patent** (10) **Patent No.:** **US D1,113,019 S**
(45) **Date of Patent:** **** Feb. 10, 2026**

(54) **STEAM CLEANER**

(71) Applicant: **SHARKNINJA OPERATING LLC**,
Needham, MA (US)

(72) Inventors: **Jeremy McDaniel**, Plainville, MA
(US); **Scott B. Niedzwecki**, Plainville,
MA (US); **Ben Burris**, Newton, MA
(US)

(73) Assignee: **SharkNinja Operating LLC**,
Needham, MA (US)

(**) Term: **15 Years**

(21) Appl. No.: **29/945,110**

(22) Filed: **May 31, 2024**

(51) LOC (15) Cl. **15-05**

(52) U.S. Cl.
USPC **D32/16**

(58) **Field of Classification Search**

USPC D13/107-109; D15/199; D21/526, 578;

(57) **CLAIM**

The ornamental design for a steam cleaner, as shown and described.

DESCRIPTION

FIG. 1 is a perspective front, top left view of a steam cleaner, showing the claimed design;

FIG. 2 is a perspective front, top right view thereof;

FIG. 3 is a perspective rear, top left view thereof;

FIG. 4 is a perspective rear, top right view thereof; and

FIG. 5 is a front view thereof;

FIG. 6 is a rear view thereof;

FIG. 7 is a right view thereof;

FIG. 8 is a left view thereof;

FIG. 9 is a top view thereof; and,

FIG. 10 is a bottom view thereof.

The broken lines in the drawings depict unclaimed subject matter that forms no part of the claimed design.

1 Claim, 7 Drawing Sheets
